UNITED STATES PATENT OFFICE.

FREDRICK A. LA ROCHE, OF NEW YORK, N. Y.

QUICK-BREAK ELECTRICAL SWITCH.

SPECIFICATION forming part of Letters Patent No. 718,775, dated January 20, 1903.

Application filed December 14, 1901. Serial No. 85,883. (No model.)

To all whom it may concern:

Be it known that I, FREDRICK A. LA ROCHE, a citizen of the United States, residing in the city, county, and State of New York, have

5 invented new and useful Improvements in Quick-Break Electrical Switches, of which the following is a specification.

My invention in quick-break electrical switches relates to improvements in the means 10 for effecting a rapid or instantaneous break, whereby a minimum of arcing at the contact-points is permitted when the switch is being thrown into an open position, while the circuit which the switch is adapted to control 15 is energized; and the object of my invention is to provide a means whereby any ordinary bridged type of electrical switch may be readily equipped with a quick-break device arranged in accordance with my invention 20 and to provide for such device a controller, whereby the same may be actuated by the operator in a manner more convenient than by any of the older devices adapted to accomplish a similar purpose of which I am at present aware; and a further object of my invention 25 is to render the said device capable of being attached with facility to the same support as that of the elements which enter into the switch structure. The different features 30 of my invention by which I attain these objects are illustrated in the drawing hereto attached, which forms part of this specification, wherein—

A is the switch-base, which is usually composed of marble or slate, upon which the switch B is mounted in the usual manner. Upon the switch-base A, I mount a motor or projector C in the manner shown in the drawing, in which I have illustrated the same 35 40 by a cross-sectional view taken through the center of the motor or projector, so as to show the different operating parts. The head D of the projector is secured to a plunger E, and a thrust-spring F, contained within the tube 45 G, is arranged in a manner so as to bear and thrust against the plunger E, so as to exert an outward pressure against the latch or releasing-hook H, which when thrown into the 50 position of the dotted line by the lever I will release the head D, allowing the compression-spring F to act directly upon the cross-bar of the switch B, so as to force it toward that

position indicated by the dotted lines or into that position in which the switch will be opened with sufficient force to throw the latter open rapidly. 55

To energize the motor or projector C, the switch is thrown into a closed position, or that shown by the full lines in the drawing, until the cross-bar of the switch has forced the head D into engagement with the hook of the latch H. 60

It is obvious that the switch B may be manipulated by hand without disturbing the projector. It is also obvious that my projector or motor may be attached to the base of a large variety of switches of a type similar to that shown in the drawing, thereby converting the usual type of switch referred to into a quick-break switch. 65

I am aware that quick-break switches have been in vogue previous to my invention, wherein a spring-actuated plunger was unlatched by thermostatic provision to automatically effect the quick opening of the 70 switch and that it has also been proposed to provide a switch turning in bearings and adapted to break at two points, with a handle designed to be held in an open position by contractile springs attached to a turning 75 part of the switch and to the base, respectively, the handle when turned to the closed position being retained therein by a spring-engaged latch having a finger-piece for effecting the release of the lever. My invention will be readily distinguished from such 80 constructions in that I combine with a knife-switch having engaging clips a spring-actuated motor or projector in a position to be energized when the switch is engaged with 85 the clips, said motor including a head against which the switch bears when so engaged, a latch independently movable of but restraining said head when pressed back, and a stem connected with said latch carrying a finger-rest and extending in such convenient position contiguous to the several parts that a slight finger-pressure will disengage the latch from the head, release the motor or projector, and permit it to quickly throw the switch 90 from the clips. The location of the tube G in the base not only conduces to compactness, but affords ample range for the thrust-spring and plunger-rod. It also serves for the 95 100

convenient application of the securing-nuts both at the front and back of the base.

Having now particularly described and ascertained the nature of my said invention 5 and in what manner the same is to be performed, I declare that what I claim is—

1. In a manually-operated electrical switch, the combination with a switch and its contacts, of a motor adapted to be energized by the pressure contact of the switch when moved to the closed position, a latch for restraining said motor independent of said switch, and a finger-operated lever for moving said latch to release the motor and permit it to outwardly force the switch. 15

2. In a manually-operated electrical switch, the combination with a switch and its contacts, of a motor including a tube located in the switch-base and containing a thrust- 20 spring acting upon a plunger rod and head, said head being adapted to be moved back by the pressure contact of the switch, to energize the spring, a latch movable independently of the head but adapted to restrain the 25 same when pressed back and a finger device

for moving said latch to release the head and permit it to outwardly force the switch.

3. In a manually-operated electrical switch, the combination with a switch and its contacts, of a motor including a tube located 30 and secured in the switch-base and containing a thrust-spring acting upon a plunger rod and head, the latter being adapted to be moved back by the pressure contact of the switch to energize the spring, a latch movable independently of but vibrated by the head upon its rearward movement to restrain the same, and a lever at the rear of the switch connected to the latch, extending beyond the switch and carrying a finger-rest to 35 permit it to be operated to release the latch and allow the motor to outwardly force the switch.

In testimony whereof I have signed my name to this specification in the presence of 45 two subscribing witnesses.

FREDRICK A. LA ROCHE.
